CLAIM

The ornamental design for an electronic display device, as shown and described.

DESCRIPTION

FIG. 1 is a perspective view illustrating an electronic display device design according to our design;
FIG. 2 is a back view thereof;

FIG. 3 is a front view thereof;

FIG. 4 is a side view thereof;

FIG. 5 is another side view thereof;

FIG. 6 is a top view thereof;

FIG. 7 is a bottom view thereof; and,

FIG. 8 is a bottom perspective view thereof.

Broken lines shown in the drawings illustrate portions of the electronic display device, and form no part of the claimed design.

1 Claim, 5 Drawing Sheets
